MAGNET CHARGER

George W. Stover, Boonton, N. J., assignor to Radio Frequency Laboratories, Inc., Boonton, N. J., a corporation of New Jersey

Application October 23, 1956, Serial No. 43,470

Term of patent 14 years

(Cl. D26—15)

The single figure is a perspective view of a magnet charger, showing my new design. The back, thereof, is a conventional plane panel.

I claim:

The ornamental design for a magnet charger, substantially as shown and described.
